UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

NAILING MECHANISM.

Application filed March 26, 1923. Serial No. 627,743.

This invention relates to nailing mechanisms and is of particular utility in connection with shoe nailing machines.

It is desirable that certain of the tacks and nails which are driven into a shoe in the course of its manufacture should be "toed in", as it is called, at a substantial angle in order to insure against any of their points being deflected outward and emerging from the side of the shoe. This is conspicuously true of the nails which are driven in the heel seat portion of the shoe and, in the illustrative machine herein disclosed in detail, the invention is embodied in a die 10 for a heel seat nailing machine.

The object of the invention is to provide an improved mechanism which will drive nails or tacks in such a manner that they will enter the work in a direction at an angle 20 to the direction of the force applied to the driver or drivers and which shall, therefore, make practicable the attainment of the desirable results above indicated, without the necessity of tipping the shoe during the 25 nailing process, as is the common practice when using a loose nailing machine in the performance of this operation.

Unsuccessful attempts have been made in the past to drive nails or tacks in the manner stated, by using nailing dies having nail and driver guiding passages comprising two or more portions angularly related to each other, but the breakage of drivers was so great that such devices had to be 35 abandoned. The drivers are made of steel wire or rod and are sufficiently resilient to withstand flexure through a very considerable total angle in a smooth, or gradual curve, but any attempt repeatedly to bend them abruptly at any one point inevitably results in breakage.

The present invention solves the difficulty by providing a nailing die having a curved nail guiding passage, as distinguished from a nail guiding passage composed of straight elements joining at an angle. In the illustrated structure the nail and driver guide comprises an integral tube whose longitudinal axis is bent to a convex curve. When a plurality of curved nail and driver guiding passages or elements are arranged in converging relation, as shown, a gang of nail drivers, corresponding in number, is pro-

vided and gang nailing may be readily performed, with the nails toed in as desired.

One satisfactory practical embodiment of the invention is illustrated in the accompanying drawings, in which

Fig. 1 is a plan view of a heel seat nailing die; and

Fig. 2 is a vertical section of the same taken on the line 2—2 of Fig. 1.

In the drawings 10 indicates a die block provided with a number of chambers 12 equal to the number of nails to be driven. In each of the chambers 12 is suspended a nail guiding tube 14 which may conveniently be formed with a spherical portion 16 at its upper end.

A hemispherical seat 18 is formed in the upper side of the die block 10 at the upper end of each of the chambers 12, and similar hemispherical cavities are formed in the lower face of a cover plate 20 which is secured to the block and serves to retain the balls 16 in their respective seats. The longitudinal axis of each of the tubes 14 is convexly curved as is clearly shown in Fig. 2. While the curvature of the bore 22 of the tube, which constitutes the nail and driver guiding passage, may or may not extend the full length of the tube, it is important that it be gradual and smooth and devoid of any sharply diverging or re-entrant portions. It is to be understood that the expression "convexly curved", wherever used in this specification and the following claims, is used in the accepted geometrical sense as defining a curve which cannot be cut by a single straight line at more than two points no matter how far produced, and distinguishing from a re-entrant curve the direction of the flexure of which changes.

In the illustrated construction the nail and driver guides are arranged to converge downwardly and, while their mountings are such as to permit them to swing freely about the centers of their spherical upper ends 16, rotation is prevented by a pin 24 projecting from the ball 16 into a vertical slot 26. The slots 26 are arranged radially with respect to the nailing pattern and constrain the curved tubes 14 to swing in their planes of curvature. The plate 20 is apertured at 28 to permit the passage of the nails and drivers 30, 32 into the guiding passage 22.

The upper end of the guiding passage 22 is flared, as shown at 34, sufficiently to insure that the passage shall always be free regardless of the angular position of the tube.

5 The drivers are mounted in the usual driver block 36 in a pattern identical with the pattern of the apertures 28 in the plate 20 and are actuated by a vertically reciprocating cross head 38 in which the driver block is mounted. The drivers are normally straight and are sufficiently flexible to enable them to follow the passages 22 without permanent distortion of the drivers, which are sufficiently resilient to cause them to become straight when withdrawn from the guiding passages.

20 40 indicates a pattern plate which is detachably secured upon the under side of the die block 10 and is provided with a frustoconical opening 42 for the lower end of each of the tubes 14. It is contemplated that a set of such pattern plates, having different desired nailing patterns, be provided, the pattern plates being readily interchangeable when it is desired to change from one size nailing to another. It will be understood that, by reason of the fixed pivotal axis about which the tubes 14 swing when their adjustment is changed, a change of the 25 30 nailing pattern from one size to another will change the degree to which the driven nails toe in and that the nails will toe in more in shoes of small sizes than in those of larger sizes, which is desirable.

35 40 The under sides of the various pattern plates 40 are hollowed out, as shown at 44 to fit the heel seats of the respective sizes of shoes and in practice, the proper plate 40 for the shoe to be operated upon having been selected, the shoe will be jacked up against the concave surface 44 against which the outer sole 46 will be pressed. The required number of nails may now be driven through the outersole 46, the inturned edges 45 of the upper, counter and lining 48, 50, 52 and clenched on the inner face of the insole 54.

50 55 While it is apparent upon inspection of the ordinary nail drivers, such as those shown at 32, that they may be easily bent into a considerable curve, practical advantage of this characteristic has never been taken heretofore, possibly because of the impracticability of drilling an axially curved guiding passage in the solid nail blocks which have been used. The utmost that has been accomplished in this direction was the drilling of straight holes joining at an angle and, as previously stated, this was found to exert a destructive bending upon the drivers.

60 65 By employing integral tubes as nail and driver guides it is comparatively easy to bend them to the desired smooth, continuous curve through which the drivers will operate readily without damage and thus, for

the first time in the art, it becomes practical to drive a gang of nails which are toed in as desired.

Having described the invention, what is claimed as new and desired to be secured 70 by Letters Patent is:

1. In a shoe nailing machine, the combination of a plurality of solid, normally straight, substantially parallel, resilient drivers, a corresponding plurality of curved 75 guides through which said drivers are movable, and means for applying force to all of said drivers in the same direction.

2. In a shoe nailing machine, the combination of a plurality of solid, normally straight, substantially parallel, resilient drivers, a corresponding plurality of convergently curved guides through which said drivers are movable, and means for applying 80 85 force to all of said drivers in the same direction.

3. In a shoe nailing machine, a nailing die having a plurality of curved nail guides each having one of its ends located at the work 90 engaging face of the die and being mounted for pivotal movement about a point at its opposite end.

4. Nailing mechanism having, in combination, a curved driver guide, a normally straight, resilient driver arranged to enter and move through said guide, and means 95 for pivotally supporting said guide at the end at which the driver enters.

5. Nailing mechanism having a curved nail and driver guide which is angularly 100 adjustable, in the plane of its curvature, about a point at one of its ends.

6. Nailing mechanism having, in combination, a smoothly curved driver guiding passage, and a solid driver normally of a 105 shape different from that of said passage and sufficiently resilient to follow the passage without permanent distortion of the driver.

7. Nailing mechanism having, in combination, a curved driver guiding passage and a solid normally straight resilient driver having sufficient flexibility to enable it to follow the passage and sufficient resiliency to cause it to become straight when withdrawn 110 115 therefrom.

8. A nailing machine having, in combination, a curved driver guiding passage, a solid normally straight, resilient driver arranged to move in said passage, and a rectilinearly moving driver actuator. 120

9. Nailing mechanism having a curved nail guide which is angularly adjustable, in the plane of its curvature, about a point in 125 its axis.

10. In a shoe nailing machine, a nailing die having curved nail guiding passages constructed and arranged to cause nails to enter the shoe at different angles to the surface in shoes of different sizes. 130

11. In a shoe nailing machine, a nailing die having curved nail guiding passages constructed and arranged to cause nails to toe in more in shoes of small sizes than in those of larger sizes.

12. A nailing die having curved nail and driver guides mounted for pivotal movement about separate points remote from the work engaging face of the die.

10 13. A nailing die having a driver guide

comprising an integral tube whose longitudinal axis is bent to a convex curve.

14. A nailing die having a nail and driver guide comprising a tube whose longitudinal axis is bent to a convex curve, said tube ¹⁵ having a spherical portion by which it may be supported for pivotal movement.

In testimony whereof I have signed my name to this specification.

JOHN B. HADAWAY
